UNITED STATES PATENT OFFICE

SIDNEY Y. WHITE, OF NEW YORK, N. Y., ASSIGNOR, BY MESNE ASSIGNMENTS, TO RADIO CORPORATION OF AMERICA, OF NEW YORK, N. Y., A CORPORATION OF DELAWARE

ELECTRICAL AMPLIFIER CIRCUITS

Application filed August 11, 1925. Serial No. 49,521.

While my invention relates generally to electrical amplifier circuits, it refers particularly to means for transferring alternating currents from the output circuit of one amplifier into the input circuit of a succeeding amplifier. It is of particular advantage in connection with three electrode vacuum tube amplifiers in so-called cascade or tandem combinations, particularly in radio receivers employing cascaded three electrode vacuum tubes as amplifiers in the high frequency portion of such receivers.

An object of my invention is to provide a coupling means for energy transfer from one amplifier to another, in which the rate of energy transfer may be caused to vary in any manner desired with variation of frequency of the currents being handled by the amplifiers. A particular object is to maintain the rate of energy transfer constant over a wide range of frequencies.

Another object of my invention is an arrangement in the coupling which will prevent the direct current energizing potentials necessary for rendering the amplifiers operative from being impressed upon other than the desired amplifier electrodes while employing common sources of such potentials for a plurality of amplifiers.

A further object of my invention is to limit and control the reaction of the output circuit of an amplifier upon its input circuit which accompanies resonant abstraction of energy from the output circuit where the inherent capacity path in such amplifiers permits such reaction to take place.

It is an object of my invention to provide a coupling whose constancy or predetermined variation with frequency is automatically and electrically provided for, and is simply and readily applied to existing amplifier circuits.

In a co-pending application Serial No. 48,936, filed August 7, 1925, I have described and illustrated diagrammatically an electri-

cal coupling means with which energy transfer may be made to remain constant with variation of frequency or may be caused to vary in a predetermined manner with variation of frequency, the description referring to 50 electrical circuits in general. I have discovered that the coupling means so described may, with proper arrangements, be applied to amplifier circuits with many advantageous results, particularly in the case of three- 55 electrode vacuum tube amplifiers.

My present invention will be best understood by reference to the figure in the accompanying drawing in which my invention is shown employed in the high frequency portion of a radio receiver having two three-electrode vacuum tubes in this portion. The element X represents an antenna or collector circuit completed to ground G through a condenser C3 and an inductance element L1, 60 and may or may not include a condenser C1, depending upon whether or not the physical characteristics of the antenna make such a condenser desirable. A tunable absorbing circuit, including an inductance element L2, 65 a variable condenser C2 and the condenser C3, is coupled to the antenna circuit through the connection of the antenna around the condenser C3, and through having the inductance element L1 and the inductance element L2 inductively related. As more fully explained in my copending application, the energy transfer between the antenna circuit and the tunable absorbing circuit due to the electrostatic coupling through the condenser 70 C3 decreases with increase of frequency, and the energy transfer due to the electromagnetic coupling through the inductive relation of coils L1 and L2 increases with increase of frequency. Thus, with the polarity 75 of the inductive coupling chosen such that the currents in the absorbing circuit due to electrostatically and electromagnetically transferred energy are in phase or aiding, the decrease of transfer with frequency of 80

85 90 95

the one form of coupling is opposed by the increase of the other. The degree with which the transfer through the electrostatic coupling changes with frequency can be readily controlled through appropriate choice of the relative capacity values of the coupling condenser C3 and the variable tuning condenser C2, since coupling is a function not only of the capacity common to the two circuits, but involves the non-common capacity as well. Thus the electro-static coupling may be caused to vary in a pre-determined way with frequency, and combined with the electro-magnetic coupling give a resultant coupling to transfer energy predetermined to either increase or decrease with frequency increase, or to remain constant with frequency change.

The absorbing circuit is shown as the input circuit to the three-electrode vacuum tube amplifier VT1, and as tunable for selective absorption from the antenna circuit through variation of the condenser C2. The output circuit of the vacuum tube VT1 is shown as including an inductance element L'1 and a condenser element C'3 as in the case of the antenna circuit just previously described. An absorption circuit, including the inductance element L'2, variable condenser C'2 and condenser C'3, which is the input circuit of a second vacuum tube VT2, is shown associated with the output circuit in the manner described for the association of the absorption circuit to the antenna circuit and may, through like adjustments described with respect to the coupling for the former circuits, be made to transfer energy at a rate remaining constant with frequency or varying in any predetermined manner. Vacuum tube VT1 is illustrated as connected for straight amplification work through having its grid return lead connected to the negative side of the filament energizing source. Vacuum tube VT2 is shown as connected for detection work through having the well-known grid leak-stopping condenser combination GL, and having its grid return connected to the positive side of the source for energizing the filament. The transformer T in the output circuit of vacuum tube VT2 passes the detected currents on to an audio frequency amplifier or direct to a translating device.

The wires to terminals marked +A—B, —A, and +B, indicate the usual connections for energizing from batteries or other suitable energy sources the output circuits and the filaments of the vacuum tubes and are thought to require no description in detail.

In view of the condenser C'3 interrupting the output circuit of vacuum tube VT1 for direct current flow, it is necessary to provide a shunt path around this condenser, which is shown as the path including the inductance element L3. In order to compel the amplified alternating currents to seek the path

containing the condenser C3, it is necessary to provide the inductance L3 with sufficient impedance to accomplish the result. In radio frequency work such a device is commonly termed a "radio frequency choke," 70 and is well known to the art. The main alternating current path is therefore from the plate of tube VT1 through coil L'1, and condenser C'3 to the filament system, and in taking this path transfers energy to the tunable input circuit of tube VT2 both electromagnetically and electrostatically in the manner hereinbefore described and subject to the adjustments described. 75

It will be seen that the condenser C'2 acts to prevent positive high potential impressed upon the plate of vacuum tube VT1 from reaching the grid of vacuum tube VT2. At the same time the arrangement does not prevent properly biasing the grid of vacuum tube 80 VT2 with respect to its filament. It will be seen that the positive potential, due to connecting the grid return of vacuum tube VT2 to the positive side of the filament energizing source, reaches the grid through the conductive path provided by the inductance L'2 and the grid leak resistance. 85

It is well known in vacuum tube practice that the inherent capacity between the elements in the tube, particularly between the grid and plate elements, is a disturbing factor of no little moment, particularly in high frequency work, the disturbance arising through this capacity providing a path through which the amplified energy in the plate circuit can in part flow to the grid circuit to augment, when in correct phase, the grid circuit energy, often resulting in the system becoming a generator of oscillations. The amount of energy which escapes to the grid circuit depends upon the extent of reaction of the plate circuit on the amplified energy, or in other words, the counter electromotive force set up in the plate circuit, and the affect of this plate-circuit-originated energy upon the action of the tube depends upon its phase relation with respect to the original energy in the grid circuit. The reaction of the plate circuit upon the energy and the phase relations depend upon the reactance characteristics of the plate circuit. The disturbing tendency to oscillate is maximum when the output circuit, during the process of tuning, comes to that point near resonance with the input circuit where the inductive reactance predominates. In the arrangement shown I prefer to make the characteristics of the inductance element L'1 and the condenser C'3 such that the output circuit proper of the vacuum tube VT1 is never near resonance with the input circuit of the tube within the range of frequencies for which the receiver is designed, and therefore no oscillation producing reaction results from this circuit alone. 90

On the other hand, I abstract 95

energy from the output circuit into the absorbing circuit forming the input circuit of the succeeding vacuum tube, and this abstraction of energy produces a greater reaction than is had due to the plate circuit alone, as well as varies the nature of the reaction from inductive to capacitive and vice versa as the absorbing circuit may be tuned from one side to the other of resonance in carrying out the tuning adjustments. The degree of reaction, however, will depend upon the degree of coupling between the two circuits. When I desire to keep the reaction sufficiently low to prevent the system from oscillating, I make the coupling between the two circuits loose, preferably by making the number of turns in the coil L'_1 small with respect to the number of turns on the coil L'_2 , and the value of the condenser C'_s large with respect to the value of the condenser C'_2 . With the coupling made sufficiently loose, and the constants involved in the coupling adjusted so that the rate of energy transfer remains constant throughout a wide range of frequencies, as heretofore described, I am enabled to continuously tune the absorbing circuit in the input circuit of vacuum tube VT2 in consonance with the input circuit of vacuum tube VT1 without throwing the system into oscillations, and at the same time obtain a most efficient transfer of energy throughout the desired range of frequencies. It will be appreciated that this control over the reaction is electrically automatic. In the ordinary inductive form of coupling, if the coupling is made sufficiently loose not to have oscillations at the higher frequencies of a desired band, it becomes inefficient in energy transfer at the lower frequencies of the band. It will be seen that my system is extremely simple and inexpensive, requiring for ordinary radio practice the addition of an inexpensive fixed condenser C'_s and an inexpensive radio frequency choke L_3 , and the use of these elements will in many systems, permit the removal of other elements used for preventing oscillations.

While I have described and illustrated my invention in connection with its use in a radio receiver, many other applications will be readily apparent to those skilled in the art, and I do not wish to be limited in its scope to the chosen system for descriptive purposes.

Having fully described my invention, I claim:

1. An electrical system composed of an amplifier of alternating currents, a tunable input circuit, an output circuit, an internal path in said amplifier connecting said output circuit to said input circuit, a tunable absorbing circuit associated with said output circuit, and means for limiting amplified energy feed-back through said internal path comprising means for loosely coupling said ab-

sorbing circuit to said output circuit and electrical elements maintaining said coupling constant while said absorbing circuit is tuned in consonance with said input circuit.

2. An electrical amplifying system including a three electrode vacuum tube, an adjustable period circuit connected to the input electrodes of said tube, an output circuit, a responsive device, and means for controlling the reaction of said output circuit and abstraction of energy therefrom for said responsive device over a wide range of frequencies that a predetermined effect in said responsive device with frequency is obtained, including a circuit coupled to said output circuit adapted to be adjusted in period in consonance with said adjustable period input circuit, and across which second adjustable circuit said responsive device is connected, said coupling including a pair of coupling elements transferring energy in phase, one of which couplings increases in effect with frequency increase and the other of which couplings decreases in effect with frequency increase, the relative values of said couplings being chosen to give the said predetermined effect over a wide range of frequencies.

3. In an electrical system including a three electrode vacuum tube, a selectively variable input circuit and an output circuit, said tube having internal capacity through which amplified energy may be regeneratively transferred from said output circuit to said input circuit in degree dependent upon the value of said capacity, frequency of current energy, and potential of reaction to current flow in said output circuit, the method of controlling the regenerative conduct of said system from frequency to frequency as said variable input circuit is varied which consists of selectively absorbing energy both electrostatically and electromagnetically in phase from said output circuit in consonance with the varying of said input circuit at a rate to produce an absorption reaction on said output circuit to cause a desired order of regeneration through said tube capacity, controlling said selective absorption electrostatically whereby said electromagnetic absorption decreases with frequency decrease, and so relating the variation of electrostatic absorption to the necessary electrostatic variation for selective absorption that said electrostatic absorption increases with frequency decrease at such rate that the regeneration remains substantially constant with frequency change.

4. In an electrical system including a three electrode vacuum tube, a selectively variable input circuit and an output circuit, said tube having internal capacity through which amplified energy may be regeneratively transferred from said output circuit to said input circuit in degree dependent upon the value of said capacity, frequency of current energy,

and potential of reaction to current flow in said output circuit, the method of controlling the regenerative conduct of said system from frequency to frequency as said variable input circuit is varied which consists of selectively absorbing energy from said output circuit in consonance with the varying of said input circuit at a rate to produce an absorption reaction on said output circuit to cause a desired order of regeneration through said tube capacity, dividing said absorption between two couplings one of which transfers energy in phase with the other and increasingly with increase of frequency, and the other of which transfers energy decreasingly with increase of frequency, and selecting the rate of change of energy transfer with frequency of at least one of said couplings to produce a predetermined character with frequency of combined absorption reaction on said output circuit, whereby the regeneration with frequency is controlled in a desired way.

5. In an electrical system including a three electrode vacuum tube, a selectively variable input circuit and an output circuit, said tube having internal capacity through which amplified energy may be regeneratively transferred from said output circuit to said input circuit in degree dependent upon the value of said capacity, frequency of current energy, and the potential of reaction to current flow in said output circuit, the method of controlling the regenerative conduct of said system from frequency to frequency as said variable input circuit is varied which consists of selectively absorbing energy from said output circuit in consonance with the varying of said input circuit at a rate to produce an absorption reaction on said output circuit of potential to cause a desired degree of regeneration through said tube capacity, and controlling said rate of selective absorption from said output circuit from frequency to frequency to produce reactions on said output circuit which, combining with other reactions of said output circuit, cause a desired frequency-to-frequency character of regeneration.

6. In an electrical system including a source of alternating currents of a wide range of frequencies, the electrical conduct of said source towards currents of different frequencies depending upon the nature of the reactions to said currents of different frequencies of a circuit connected to the output terminals thereof, the method of controlling said reactions with frequency as the current output of said source is changed from frequency to frequency which consists of selectively absorbing energy both electrostatically and electromagnetically in phase from said output circuit in frequency consonance with the currents therein to selectively create absorption reaction thereon, controlling said

selective absorption electrostatically whereby said electromagnetic absorption decreases with frequency decrease, and so relating the variation of electrostatic absorption to the necessary electrostatic variation for selective absorption that said electrostatic absorption increases with frequency decrease at such rate that the effect of said electromagnetic absorption on the reactions of said output circuit with frequency is modified in a desired way.

7. In an electrical system including a source of alternating currents of a wide range of frequencies, the electrical conduct of said source towards currents of different frequencies depending upon the nature of the reactions to said currents of different frequencies of a circuit connected to the output terminals thereof, the method of controlling said reactions with frequency as the current output of said source is changed from frequency to frequency which consists of selectively absorbing energy from said output circuit by way of a coupling which transfers energy increasingly with frequency increase in frequency consonance with the currents therein to selectively create absorption reaction thereon, further simultaneously selectively absorbing energy from said output in phase with said first selective absorption by way of a coupling which transfers energy decreasingly with frequency increase, and selecting the rate of change of energy transfer with frequency of one of said couplings to produce a predetermined character with frequency of combined absorption reaction on said output circuit whereby the conduct of said source with frequency is controlled in a desired way.

8. In a selective current amplifying and relaying system including a three electrode vacuum tube having internal capacity, a selectively variable input circuit, an output circuit, a second circuit selectively variable by capacity variation in consonance with said input circuit coupled to said output circuit, and a responsive device connected across said second variable circuit, whereby the amplifying and relaying to said responsive device varies with frequency by reason of a resultant of variation with frequency of the effect of said internal capacity of said tube, the reaction of the elements in said output circuit through said internal capacity, the usual inconstant reaction of said capacitively variable second circuit on said output circuit, and the usual inconstant transfer of energy from said output circuit to said second variable circuit, the method of maintaining the level of amplified energy delivery to said responsive device substantially constant from frequency to frequency as said variable circuits are varied, which consists of transferring the energy from said output circuit to said second variable circuit through a

- pair of couplings acting in phase, and controlling the rate of change of energy transfer with frequency through one of said couplings to produce varying effects with frequency in reaction on said output circuit and energy transfer therefrom which in combination form a resultant effect at said responsive device having a frequency characteristic substantially the reverse of that of the resultant of said varying effects. 5
9. In an electrical system the combination of a three electrode vacuum tube having inherent capacity between its electrodes, a selectively variable input circuit, an output circuit, and means for controlling the regenerative conduct of said system from frequency to frequency as said input circuit is varied comprising a circuit variable in consonance with said input circuit, and a pair of couplings between said output circuit and said second variable circuit transferring energy therebetween in aiding phase to produce a combined absorption reaction on said output circuit, one of said couplings transferring 20 energy increasingly with increase of frequency, and the other of said couplings transferring energy decreasingly with increase of frequency, the rate of transfer of said second coupling from frequency to frequency being 25 governed by a predetermined relation between said coupling element and a variable element in said second variable circuit. 30
10. In an electrical system the combination of a source of alternating currents of a wide range of frequencies, an output circuit, the electrical conduct of said source towards currents of different frequencies depending upon the nature of the reactions of said output circuit to said currents, and means for 35 controlling the electrical conduct of said source from frequency to frequency through control of said reactions comprising a circuit variable in period over said wide range of frequencies coupled to said output circuit 40 through a coupling which changes the absorption reaction of said variable circuit on said output circuit as varied from frequency to frequency, and a second coupling between said circuits in phase accord with said first coupling, said second coupling being adapted 45 to change the absorption reaction of said variable circuit on said output circuit from frequency to frequency inversely to the change produced by said first coupling. 50
- 55 11. In an electrical system the combination of a source of alternating currents of a wide range of frequencies, an output circuit, and means for maintaining the relation of the internal impedance of said source to the output impedance substantially constant from frequency to frequency of selected current output from said source comprising a circuit variable in period over said wide range of frequencies coupled to said output circuit through a pair of couplings in phase 60
- accord, one of said couplings inherently increasing the mutual relation between said variable circuit and output circuit with variation of said variable circuit to decrease the period thereof, and the other of said couplings having such dependency upon the reaction of the variable element of said variable circuit that variation thereof to increase the period of said circuit produces an increase in the mutual relation between 70 said variable circuit and output circuit substantially of reverse character from frequency to frequency to that of said first coupling. 75
12. In an electrical system the combination of a three electrode vacuum tube having inherent capacity between its electrodes, a selectively variable input circuit, an output circuit, and means for controlling the regenerative conduct of said system from frequency to frequency as said input circuit is varied comprising a circuit electrostatically variable in consonance with said input circuit, an electromagnetic coupling between said output circuit and said second variable 80 circuit, and an electrostatic coupling between said circuits in phase accord with said electromagnetic coupling, said electrostatic coupling having such dependency upon the value of the variable electrostatic element in 85 said second variable circuit that the varying of said element produces a desired characteristic of electrostatic energy transfer with frequency which combines with the uncontrolled electromagnetic energy transfer characteristic 90 to produce a resultant characteristic representing a desired reaction on said output circuit whereby regeneration is controlled in a desired way with frequency. 95
13. In a selective radio frequency amplifying system the combination of a three electrode vacuum tube having inherent capacity between its electrodes, a variable period input circuit, an output circuit, a second variable period circuit, a second vacuum tube connected directly across said second variable circuit, and means for maintaining the amplified energy level selectively delivered to said second tube substantially constant from frequency to frequency as said variable circuits are adjusted in substantial consonance 100 while preventing oscillation production throughout the tuning range of said system, comprising a pair of in-phase couplings between said output circuit and said second variable circuit, the combined coupling effect of said couplings being sufficiently loose that the reaction of said output circuit is not modified by said coupling sufficiently to produce 105 regenerative reaction through said tube capacity sufficient for oscillation production, one of said couplings being increasingly effective with frequency increase, and the other of said couplings being decreasingly effective with frequency increase, and so depend- 110
- 115
- 120
- 125
- 130

ent upon the value of the variable tuning element of said second variable circuit that selection of the relative values of the coupling element and the tuning element permits of producing a coupling-frequency characteristic that combines with the characteristic of said first coupling to produce a regenerative reaction and an energy transfer which combine to maintain a substantially constant energy delivery to said second vacuum tube.

10 In testimony whereof I affix my signature.
